BED AND THE LIKE

André Pupier, Paris, France

Application November 30, 1932, Serial No. 644,987
In France December 2, 1931

2 Claims. (Cl. 128—74)

This invention relates to a new arrangement of resting pieces of furniture (beds, bedsteads, mattresses, litters, divans, chairs or folding arm-chairs or rocking-chairs, chaise-longues, benches or the like) in order to allow for preventing or curing stomach sickness in general and more particularly the nausea of gravid women, seasickness and similar sickness on board of terrestrial or aerial transporting means, mountain-sickness and so on.

10 A principal feature of the invention consists in the provision of means for lowering the part of the resting pieces of furniture which supports the head or the upper part of the body below the horizontal plane forming the upper part of the piece of furniture or, more exactly, below the horizontal or substantially horizontal plane of support for the body of the person resting on said piece of furniture, in order to cause an afflux of blood to the head in general and more particularly to the "medulla oblongata" and thus to prevent or cure the sickness.

20 Another feature of the invention consists in that the lowering and the raising of the part of the piece of furniture supporting the head or the upper part of the body are effected through a mechanical, electrical, hydraulic or pneumatic control or the like of such a kind that the movable part of the piece of furniture may progressively pass—while further supporting the head or the upper part of the body of the person lying down—from the normal horizontal or substantially horizontal position to a lowered position and conversely, and, on the other hand, may remain fixed in the selected position at will.

30 Another feature of the invention resides in the fact that the control of the movable part of the piece of furniture is so arranged that the member by means of which the person resting on the piece of furniture actuates the movable part of said piece of furniture is placed immediately within the reach of the hand of the person in question in order that this person, when qualmish or stomach sick or when feeling that he or she is going to become qualmish or stomach sick, may himself or herself and without the aid of any other person and without strain effect the desired shifting for lowering or raising the movable part of the piece of furniture.

40 The invention further has for its object a particular control device by means of which the above mentioned conditions are obtained with and in which, when the movable part of the piece of furniture has reached either of the extreme 55 positions, the electric current of the shifting mo-

tor is automatically interrupted in order to avoid a deterioration of said motor and an unnecessary consumption of current.

Different modifications of the invention are shown in the appended drawings, in which

5 Figure 1 is a diagrammatical view showing a framed mattress arranged according to the invention.

Figure 2 is a plane view of Figure 1.

Figure 3 is a view similar to Fig. 1, showing a modified structure of mattress;

Figure 4 is an end view of an actuating device for the movable part of a framed spring mattress according to Figure 1.

Figure 5 is a side elevation of another form 15 of the control device.

Figure 6 is an end view of Figure 5.

Figure 7 is a plan view.

Figure 8 is a diagram of the electrical connections of a device similar to the device shown in 20 Figures 5, 6 and 7.

As shown in Figure 1, the mattress is in two sections juxtaposed edge to edge, one part, as 1, being conveniently termed the foot portion of the mattress and the other part 2 comprising the 25 head portion. The foot portion may be a relatively fixed part, whereas the head portion is movable, and in this view is shown hinged to swing upon an axis 3 next the edge toward the fixed part or foot portion. The hinging is preferably effected by use of aligned trunnions 3 and 3^a at the sides of the mattress next the upper surface thereof so as to avoid any hard or uncomfortable parts extending across the mattress.

The two abutting parts 4 and 5 of the framed 35 spring mattress forming the ends of the fixed part 1 and of the movable part 2 respectively at their opposite faces are tapered in order to permit the swinging of the part 2 with respect to the part 1 below the horizontal plane, as shown 40 in dot and dash lines at 2^a in Figure 1.

According to the alternative form of Figure 3, the movable part 2 is formed of a tight cushion inflated with air or filled with a fluid and properly proportioned so as to be when inflated, level 45 with the upper part of the fixed part 1 of the mattress. By deflating the movable part 2 by means of the three-way valve 6 arranged on the feeding pipe 7 or the discharge pipe 7^a for the fluid serving to inflate the cushion, it is possible 50 to bring the upper part 2 of the movable part of the mattress to the position shown in dot and dash lines at 2^d of Figure 3.

The invention is not limited to the specific 55 portions of fixed and movable foot and head por-

tions shown, it being understood that the length of the head portion may be increased with a corresponding decrease of the foot portion to any desired limit. However, in general, it would be sufficient for the purposes sought, to provide for a lowering of the upper part (head and torso) of the occupant's body, so that the movable part need extend usually no further toward the feet than the occupant's diaphragm, that is, to his midriff.

The control device for the movable part 2 shown in Figure 4 is formed of an electric motor 8 for driving a speed reducing device 9, the secondary shaft 10 of which is coupled through a coupling sleeve 11 with the axis 3 of the movable part 2 of the mattress. Said axis rotates in a bearing 12 mounted on the side post 13 of the bed. Said side post 13 comprises a console 14 supporting the electric motor 8 and the speed reducing device.

On the axis 3 is keyed a stirrup 15 passing under the bed and making the axis 3 a unitary part of the axis 3^a, this latter swinging in a bearing 16 mounted on the side post 17 of the bed.

The whole is arranged so that when the electric motor 8 rotates in one direction, the axis 3 is rotated and consequently the stirrup 15 and the axis 3^a in the same direction, and when the electric motor 8 rotates in the opposite direction, the axis 3, the stirrup 15 and the axis 3^a are rotated in the same opposite direction. The movable part 2 of the mattress being rigid or integral with the axes 3 and 3^a, it follows from this that, according to the direction of rotation of the electric motor 8, the movable part 2 of the mattress will be lowered below the horizontal plane or raised in order to return to a horizontal plane.

It will be apparent that the rotation of the axes 3 and 3^a can be extended in order to bring the movable part 2 above the horizontal plane for providing a support for the head or for the upper part of the body.

In Figures 5 and 7 the side post 13 of the bed has been removed in order to show to better advantage the control device for the movable part 2 of the mattress. The control device is formed here of two levers 18, 18^a operated by two cams 19, 19^a mounted on a common axis 20 running from the post 13 to the post 17 of the bed. At 12 and 12^a are shown the bearings supporting the axes 3 and 3^a of the movable part 2 of the mattress. The axis 23 of the cams 19 and 19^a carries a worm gear 21 engaging a worm 22 driven by means of a coupling sleeve 23 through speed reducing device 24 receiving its movement from the electric motor 25. The speed reducing device and the electric motor are fixed on a cross-bar 26 suspended from the posts 13 and 17 of the bed. The gear 21 and the worm 22 are contained in a conventional case 27 (shown in dot and dash lines in order to be more clearly represented) and which is fixed to the post 13 of the bed. The arms 18 and 18^a and the cams 19, 19^a are so dimensioned that for a rotation of the shaft of less than a revolution the movable part of the mattress may pass from its uppermost position, for instance from the horizontal position, to its lowermost position. If the rotation in question represents a sufficient number of degrees, the slope of the cam 19 can be so arranged that the control device is then irreversible. When causing the motor to rotate in the one direction, the movable part 2 is located as in the preceding device, and when causing the

motor to rotate in the opposite direction said part 2 is raised.

The control of the electric motor in either direction is obtained by means of a double direction contactor 28, having two working positions 28^b and 28^c and an intermediary dead center 28^a, mounted on the post 13 of the bed immediately within the reach of the hand of the person lying on the bed. It will then be sufficient, when this person desires to lower or raise his or her head 10 or the upper part of his or her body, to actuate the switch 28 in the desired direction. Owing to the position of the switch said person may do this practically without being compelled to move or, at least, by effecting only a very slight displacement of the arm and even only of the hand.

In order that the movable part 2 may be automatically stopped in its uppermost and lowermost positions, the control device may be provided with automatic means for automatically 20 stopping the motor.

In the control device with the automatic stopping device shown in Figure 8 the circuit of the shunt motor 25, the excitation coil of which is shown at 29, is fed with current by means of 25 fixed contacts 32, 33, 34, 35 coacting with movable contacts 36 and 37 respectively carried by the two cores 38-39 of the two electromagnets 40-41. The cores 38 and 39 are connected with or supported by a movable insulating piece 42 30 which carries the contacts 36 and 37 upon a common rod 43. The switch 28 comprises two contact pieces 44 and 45 sliding on two sectors 46-47 respectively. The contact piece 44 may engage either a contact piece 43 or a contact piece 48 for the extreme positions 28^b and 28^c of the switch 28. In the same manner the contact piece 45 may engage the contact pieces 50 and 51. Two pairs of contact pieces 52-53 and 54-55 are arranged in the way of a contact 56 40 carried by the switch 28. On the other hand the shaft 20 on which are mounted the cams 19-19^a carries a swinging lever 57-58 acting on a lever 59 pivotally mounted on an axis 60. The lower arm 61 of this lever 59 acts on stops 45 62-63 mounted on a sector 64 loosely mounted on the axis 60. A part 65 of the lever is connected with the axis 20 of the tilting lever 57-58 by a traction spring 66. A swinging part 67 of contact arm 61 is pivoted upon the same axis 50 with sector 64, and is adapted to be swung into one of two extreme positions over dead-center to there impinge against stops 62 or 63 under actuation of a spring 68 similar to and shown disposed in the drawings directly in front of springs 55-66 which is thereby substantially hidden from view. The sector 64 carries a contact 69 which may be shifted between two stops 70 and 71. When the sector 64 turns about its axis 60, said contact 69 passes on two contact pieces 72-73. 60

In the operation of the device, for the position 28^a of the switch 28 no current is sent to the motor, as the circuit: pole (+) of the source of current, lead 74, sector 46, contact piece 48 or 49, lead 75 or 76, contact 33, contact 36, contact 32, terminal 65 30 of the motor, armature 25 and excitation 29 of the motor, terminal 31, contact 34, contact 37, contact 35, lead 78 or 77, contact piece 50 or 51, contact 45, sector 47, lead 79, and negative pole of the source of current is interrupted either in the 70 switch 28 or on the contacts 32, 33, 36 and 34, 35, 37. When the switch is shifted to the position 28^b, i. e. for lowering the movable part 2 of the mattress, the contact 56 engages the contact piece 52-53 and the electromagnet 40 is energized by 75

the circuit: lead (+), lead 80, contact piece 52, contact piece 53, lead 81, coil 40, lead 82, and negative lead of the source of current. This momentary energization of the electromagnet 40 during the 5 passage of the contact 56 across the contact pieces 52—53 has been effective to shift the movable appliance 39, 43, 38, 43, 42, 36 and 37 in the direction of the arrow f^1 and to close the circuits 33, 36, 32 and 34, 31, 35. On the other hand, when the lever 10 28 has reached the position 28^b, it has completed the circuit: lead 74, sector 46, contact 48, lead 15, contacts 33, 36, 32, terminal 30, motor 25—29, terminal 31, contacts 34, 37, 35, lead 78, contact piece 50, sector 47, lead 79, and minus lead of the 15 source of current. The motor then begins running in the direction by which the lowering of the movable part 2 of the mattress is effected. During said lowering movement the axis 20 rotates in the direction of the arrow f . The swinging lever 20 57—58 is turned by rotation of axis 20, and one arm, as 57, engages and swings lever 59 about its axis 60 past dead center, resulting in contact arm 61 engaging stop 62 of the sector 64 and thereby abruptly throwing the sector and its contact 25 69 to the left under influence of the spring 66 until said contact engages stop 71. During its shifting movement, the contact 69 passes rapidly across contacts 72 and 73 resulting in electromagnet 41 being energized through the circuit comprising 30 the minus lead of the source of current, lead 83, coil 41, lead 84, contact piece 73, contact 69, contact piece 72, lead 83 and the plus lead of the source of current. During this momentary energization the movable assembly of the cores 39—38, 35 rod 43, insulating support 42 and contacts 36 and 37 have been shifted to the right in the direction of the arrow f^2 thus breaking the contacts 32, 33 with 36 and 34, 35 with 37 and accordingly stopping the motor. Lever 28 likewise is connected to 40 a field-reversing switch R (indicated for clarity next the motor) for effecting a reversal of the shunt current and consequent reversal of the motor when changing the lever 28 from one extreme position to the other. A shifting of the lever 28 to the position 28^a brings back the whole to the initial position. If the lever 28 is then shifted to the position 28^c, the motor 25—29 is energized to 45 rotate in the contrary direction through the cir-

cuits which are shown on the figure and when the movable part has reached the end of its raising stroke, the contact 69, being actuated in the contrary direction with respect to the preceding one, passes again before the contacts 72—73 and interrupts again the circuit, thus stopping the motor 25. 5

Fig. 1 shows a mechanical device for oscillating the portion 2 which comprises a cam 19 acting on the movable portion 2 and rotating around an axis 10 20. This cam 19 is actuated by a rocking hand lever 19^a by means of a cross chain 19^b meshing with pinions 19^c and 19^d respectively mounted on the axis 20 and on the hand lever 19^a. The periphery of the cam 19 is so designed that when 15 the portion 2 of the mattress has reached its upper position the lever 19^a can be further rotated without moving the portion 2 until the said lever is brought to a horizontal position. 20

What I claim is:

1. In a device for preventing or curing sickness a fixed mattress portion, a movable mattress portion hinged upon the said fixed portion around two horizontal trunnions, an electrical motor, a speed reducing device between the said motor and one of 25 the above said trunnions, an electric switch controlling the said electric motor for selective rotation in either direction and located at about the half of the total length of the fixed and movable mattress portions and electrical means for stopping the electric motor when the desired positions of the said movable portion have been reached. 30

2. The combination of a bedstead having two longitudinal beams, a fixed mattress portion located between said beams, a movable mattress portion also located between said beams and hinged upon the said fixed portion around two horizontal trunnions rotating in bearings carried by the above-said beams, an electric motor, a speed reducing device between the said motor and one of 40 the above-said trunnions, an electric switch controlling the said electric motor for selective rotation in either direction and located at about the half of the total length of the fixed and movable mattress portions, and electrical means for stopping the electric motor when the desired positions 45 of the said movable portion have been reached.

ANDRÉ PUPIER.
